ZAY JEFFRIES, OF EAST CLEVELAND, OHIO, ASSIGNOR TO THE ALUMINUM CASTINGS COMPANY, OF CLEVELAND, OHIO, A CORPORATION OF OHIO.

INTERNAL-COMBUSTION MOTOR.

1,347,479.

Specification of Letters Patent. Patented July 20, 1920.

Application filed October 23, 1916, Serial No. 127,152. Renewed November 8, 1919. Serial No. 336,733.

To all whom it may concern:

Be it known that I, ZAY JEFFRIES, a citizen of the United States, residing at East Cleveland, in the county of Cuyahoga and State of Ohio, have invented certain new and useful Improvements in Internal-Combustion Motors, of which the following is a specification, reference being had therein to the accompanying drawing.

10 This invention relates to an improved cylinder and piston construction for internal combustion motors.

15 The use of light weight aluminum alloy pistons in internal combustion motors has been attended by certain drawbacks. In particular it has been found necessary to provide a relatively large clearance between the piston and the cylinder wall because the alloy metal of the piston has a substantially 20 higher coefficient of expansion than cast iron which was previously used as the piston material. This large clearance has given rise to piston slap, while the motor is starting and warming up, and also to an undue leakage of lubricating oil into the combustion chamber, such excess of oil giving rise to 25 serious carbon troubles. In addition, motors with aluminum alloy pistons have tended to run cooler than those with iron 30 pistons because the higher thermal conductivity of the aluminum alloy results in a somewhat more rapid transfer of heat to the cylinder wall.

The main object of the present invention 35 is to overcome the foregoing difficulties and this is accomplished by providing for the cylinder a cylindrical liner made of an alloy metal having a coefficient of expansion approximating that of the aluminum alloy 40 of the pistons and constructed and arranged in the iron cylinder so as to permit an expansion of the liner corresponding to that of the piston.

A further object of the invention is the 45 provision of a composite cylinder comprising a cylinder casting and a liner therein constructed and arranged to permit of the expansion of the liner in relation to the cylinder casting in a manner to control the 50 working temperature of the motor.

In order that the invention and the manner of carrying it out may be clearly understood, I will now describe one form of construction embodying the invention.

In the accompanying drawings— 55

Figure 1 is a transverse vertical section of one of the cylinders of an engine embodying my improvements.

Fig. 2 is a side elevation of a cylinder liner. 60

Fig. 3 is a plan view of the liner.

Fig. 4 is a fragmentary sectional view on an enlarged scale to show the construction more clearly.

Fig. 5 is a fragmentary side elevation of 65 the upper part of the liner showing a modified form of construction.

Referring in detail to the construction illustrated, 1 designates the cylinder casting in its entirety, said casting being made of 70 iron and comprising the cylinder wall 1^a, the water jacket 1^b, suitable intake and exhaust valve passages, and the upper crank case section 1^c.

The cylinder casting has its main cylindrical chamber bored out to receive a tubular liner 2 which is made of metallic alloy having a coefficient of thermal expansion approximately equal to that of the aluminum alloy commonly employed to make 80 light weight pistons. There are different alloys more or less closely meeting these requirements, but I prefer to use an aluminum alloy having a composition adapting the liner to resist the wear of the piston, because the coefficient of thermal expansion of 85 such liner is practically identical with that of the piston material. The liner 2 has its inner surface accurately bored out to afford a suitable bearing surface for the piston. 90 At its upper end the liner is formed with an outturned flange 2^a which fits, with a slight radial clearance, in a corresponding countersink in the upper end of the cylinder casting. At its lower end the liner is formed with an 95 external enlargement or collar 2^b which fits the bore of the cylinder casting.

Between the flange 2^a and the collar 2^b the exterior of the liner is finished with an outside diameter less than the diameter of 100

the bore of the cylinder casting so that when the motor is cold this outer wall of the liner is out of contact with the surrounding wall of the cylinder casting, this clearance being 5 provided to permit the expansion of the liner when the motor warms up. I prefer to make this clearance such that when the parts reach the working temperature, the outer wall of the liner has expanded to 10 bring more or less of its surface into close contact with the surrounding wall of the cylinder casting.

If desired, the adjacent walls of the cylinder casting and liner may be given a plain 15 cylindrical finish so that when the expansion of the liner occurs its surface is brought into contact with the surrounding cylinder wall throughout its entire area. I prefer, however, to form the adjacent walls 20 so that only a part of the exterior surface of the liner is brought in close contact with the cylinder wall when the expansion occurs, and the transfer of heat to the water jacket is correspondingly checked and the motor 25 kept at a suitable working temperature. To this end, in the construction shown, I have depressed or cut away a part of the outer surface of the upper part of the liner lying adjacent the water jacket and have correspondingly depressed or cut away the entire 30 outer surface of that part of the liner extending from the water jacket down to the collar 2^b. This formation of the outer wall of the liner may readily be accomplished by 35 machining and preferably I form the depression in the upper part of the sleeve by machining a continuous spiral groove 2^c thus forming a square spiral thread 2^d, the outer surface of which comes into contact 40 with the cylinder wall when the liner expands. The amount of clearance provided between the square thread and the surrounding cylinder wall will depend upon the size 45 of the cylinder and various other factors. The upper end of the cylinder is closed by a head casting designated as an entirety 50 by 3, this casting having a water jacket 3^a communicating in the usual manner with the water jacket 1^b of the cylinder casting. The combustion space 4 formed in the head 55 casting has an extension 4^a which communicates with the inlet and exhaust passages through valve controlled openings in the usual manner; in the drawing the exhaust 60 valve is shown at 5 and it will be understood that the inlet valve is in that part of the structure which does not appear.

The sleeve or liner 2 may be secured in the cylinder in any suitable manner but I 65 prefer a construction of the character shown in which the liner is held by the cylinder head 3, the latter being firmly secured to the cylinder casting as usual by bolts (not shown). As stated above, the flange 2^a of

the liner fits the countersink of the cylinder 65 casting with a slight radial clearance. This clearance is provided to allow the upper end of the liner to expand radially when heated, the expansion of the metallic alloy liner being greater than that of the iron cylinder 70 casting. To insure an accurate centering of the upper end of the liner in the bore of the cylinder casting without interfering with the expansion referred to, I form the flange 2^a with a series of radial grooves 2', and to 75 the head casting 3 secure a corresponding number of depending round pins 6, each arranged to fit in one of the radial grooves 2'. These pins prevent lateral displacement bodily of the upper end of the liner without 80 interfering with its radial expansion. The lower end of the liner is not heated as highly as its upper end and the enlargement 2^b can be relied upon to center the said lower end, the bore of the liner at its lower end being 85 made slightly larger than at other points, if necessary, to accommodate any slight deformation of the lower end of the liner that may result from its expansion against the less expansible iron. 90

In Fig. 1 the pins 6 are shown cylindrical and the grooves 2', correspondingly, with vertical sides. If desired, this construction can be modified as shown in Fig. 5 where the pins 6^a are tapered at their lower ends 95 and the grooves 2'' formed with inclined sides. With this latter construction a very nice fit can be secured between the pins and grooves by properly setting the pins.

7 designates a piston arranged to reciprocate in the cylinder liner in the usual manner, being connected by connecting rod 8 with the crank 9 of the engine shaft 10. This piston is made of light weight metallic alloys preferably aluminum alloy such as 100 is now in use for this purpose. The piston is provided with packing rings 11 of any preferred form and construction, and, in other respects, the piston may be of any suitable form and construction. 110

Heretofore in motors with aluminum pistons a relatively large clearance has been provided for the piston, but in my improved construction the piston is fitted to the bore of the liner nearly if not quite as closely as 115 a cast iron piston would be fitted to the bore of a cast iron cylinder.

In the operation of my improved motor, the cylinder liner when cold is entirely out of contact with the surrounding cylinder 120 wall except possibly at the collar 2^b; but, as the piston and liner absorb heat from the combustion gases, they both expand until the working temperature is reached, at which point, or slightly before it, the outer 125 surfaces of the projecting thread 2^d are brought into close contact with the cylinder wall. Until this latter contact is estab-

lished, the liner is thermally insulated from the surrounding cylinder wall by the interposed envelop of air and consequently the cylinder and piston rise quickly to working 5 temperature and the motor is correspondingly easy to start. As soon as contact between the liner and the surrounding cylinder wall is established, excess heat begins to be conducted to the water jacket and the parts 10 are thus kept at suitable working temperature.

A composite cylinder, properly designed and constructed in accordance with my invention, has a peculiar automatic governing 15 action on the working temperature of the engine; for if the temperature falls to a certain value the resultant contraction of the cylinder parts causes the external surface of the liner to draw away from the wall of 20 the cylinder casting so that the conduction of heat to the latter is at once checked and the working temperature of the motor tends to build up again. This action, as stated, is automatic in its nature.

25 As has been stated, the piston, when the parts are cold, has only the minimum clearance necessary for smooth operation; and, inasmuch as both piston and cylinder liner expand together when the motor heats up, 30 no seizing of the piston occurs but, on the contrary, the small initial clearance is maintained substantially constant. I therefore entirely avoid the objectionable piston slap and oil pumping which has characterized 35 prior motors with iron cylinders and aluminum pistons.

As I have already indicated, the clearance provided between the outside diameter of the liner and surrounding cylinder wall will 40 depend upon the form and dimensions of the motor and is preferably to be determined in each case experimentally, as is also the area of contact between the liner and cylinder wall. My experience indicates that in most 45 cases the clearance in question will run between eight and fifteen thousandths of an inch for cylinders running from three to four inches in diameter.

Those skilled in the art will understand 50 that various changes in the forms and proportions of the parts may be made in carrying out my invention. The construction herein set forth is for purposes of illustration and explanation and in no sense intended as a limitation of my invention.

What I claim is:

1. In an internal combustion motor, the combination with a composite cylinder comprising an iron casting with a cylindrical 60 wall surrounded by cooling means, and a cylindrical liner secured concentrically within the said cylindrical wall, the said liner being made of a metallic alloy having a higher coefficient of thermal expansion than

the iron of the said casting and having its 65 external diameter less than the diameter of the inner wall of the casting to afford a clearance between the liner and casting adapted to be taken up by the expansion of the liner when heated by the internal combustion within the motor, of a piston arranged to reciprocate in the liner and made of a light weight metallic alloy having a coefficient of thermal expansion greater than that of the iron of the cylinder casting. 70 75

2. In an internal combustion motor, the combination with a composite cylinder comprising an iron casting with a cylindrical wall surrounded by cooling means, and a cylindrical liner secured concentrically within the said cylindrical wall, the said liner being made of a metallic alloy having a higher coefficient of thermal expansion than the iron of the said casting and having its 80 external diameter less than the diameter of the inner wall of the casting to afford a clearance between the liner and casting adapted to be taken up by the expansion of the liner when heated by the internal combustion within the motor, of a piston arranged to reciprocate in the liner and made of a light weight metallic alloy having a coefficient of thermal expansion approximately equal to that of the liner alloy. 85 90

3. In an internal combustion motor, the combination with a composite cylinder comprising an iron casting with a cylindrical wall surrounded by cooling means, and a cylindrical liner secured concentrically within the said cylindrical wall, the said liner 100 being made of aluminum alloy and having its external diameter less than the diameter of the internal wall of the casting to afford a clearance between the liner and casting adapted to be taken up by the expansion of the liner when heated by the internal combustion within the motor, of an aluminum alloy piston mounted to reciprocate in the liner with a normal working clearance when 105 the parts are cold. 110

4. In an internal combustion motor, the combination with a composite cylinder comprising an iron casting with a cylindrical wall surrounded by cooling means, and a cylindrical liner secured concentrically within the said cylindrical wall, the said liner being made of a metallic alloy having a higher coefficient of thermal expansion than the iron of the said casting and having its 115 external diameter less than the diameter of the inner wall of the casting to afford a clearance between the liner and casting adapted to be taken up by the expansion of the liner when heated by the internal combustion within the motor, and part of one 120 of the adjacent surfaces of the cylinder wall and liner being recessed to form heat insulating space between the cylinder wall and 125

liner, of a piston arranged to reciprocate in the liner and made of a light weight metallic alloy having a coefficient of thermal expansion greater than that of the iron of the 5 cylinder casting.

5. In an internal combustion motor, the combination with a composite cylinder comprising a casting with a cylindrical wall surrounded by cooling means, and a cylindrical liner secured concentrically within the said cylindrical wall, the said liner being made of metallic alloy having a higher coefficient of thermal expansion than the metal of the said casting and having its external 10 diameter less than the diameter of the inner wall of the casting to afford a clearance between the liner and casting adapted to be taken up by the expansion of the liner when heated by the internal combustion within the 15 motor, of a piston arranged to reciprocate in the liner and made of a metallic alloy having a coefficient of thermal expansion approximately the same as that of the liner 20 alloy.

25 6. A composite cylinder for internal combustion motors comprising a casting with a cylindrical wall surrounded by cooling means and a cylindrical liner secured concentrically within the said cylindrical wall,
30 the liner having its external diameter less than the diameter of the inner wall of the casting to afford a clearance between the liner and casting adapted to be taken up by the expansion of the liner when heated by
35 the internal combustion within the motor.

7. A composite cylinder for internal combustion motors comprising a casting with a cylindrical wall surrounded by cooling means and a cylindrical liner secured concentrically within the said cylindrical wall, the liner being made of metal having a higher coefficient of thermal expansion than the metal of the said casting and having its external diameter less than the diameter of the inner wall of the casting to afford a clearance between the liner and casting adapted to be taken up by the expansion of the liner when heated by the internal combustion within the motor.

50 8. A composite cylinder for internal combustion motors comprising a casting with a cylindrical wall surrounded by cooling means and a cylindrical liner secured concentrically within the said cylindrical wall, the liner having its external diameter less than the diameter of the inner wall of the casting to afford a clearance between the liner and casting adapted to be taken up by the expansion of the liner when heated by the internal combustion within the motor, and part of one of the adjacent surfaces of the cylindrical wall and liner being recessed to form heat insulating space between the cylinder wall and liner.

55

60

9. A composite cylinder for internal combustion motors comprising a casting with a cylindrical wall surrounded by cooling means and a cylindrical liner secured within the said cylindrical wall, the liner being made of metal having a higher coefficient of thermal expansion than the metal of the said casting and having its external diameter less than the diameter of the inner wall of the casting to afford a clearance between the liner and casting adapted to be taken up by the expansion of the liner when heated by the internal combustion within the motor, and part of one of the adjacent surfaces of the cylinder wall and liner being recessed to form heat insulating space between the cylinder wall and liner. 65 70 75 80

10. In an internal combustion motor, the combination with a composite cylinder comprising a main cylindrical iron wall, cooling means on the outer side of said wall, and a cylindrical liner secured concentrically within the said cylindrical wall, the said liner being made of a metallic alloy having a higher coefficient of thermal expansion than the iron of the said wall and having its external diameter less than the inner diameter of the said wall to afford a clearance between the liner and wall adapted to be taken up by the expansion of the liner when heated by the internal combustion within the motor, of a piston arranged to reciprocate within the liner and made of a light weight metallic alloy having a coefficient of thermal expansion greater than that of the iron cylinder wall. 85 90 95 100

11. In an internal combustion motor, the combination with a composite cylinder comprising a main cylindrical wall, cooling means on the outer side of said wall, and a cylindrical liner secured concentrically with- 105
in the said wall, the said liner being made of metallic alloy having a higher coefficient of thermal expansion than the metal of the said cylindrical wall and having its external diameter less than the inner diameter 110
of said wall to afford a clearance between the liner and wall adapted to be taken up by the expansion of the liner when heated by the internal combustion within the motor, of a piston arranged to reciprocate 115
in the liner and made of a metallic alloy having a coefficient of thermal expansion approximately the same as that of the liner alloy.

12. A composite cylinder for internal combustion motors comprising a main cylindrical wall, cooling means on the outer side of said wall, and a cylindrical liner secured concentrically within the said cylindrical wall, the liner having its external diameter less than the inner diameter of the said wall to afford a clearance between the liner and wall adapted to be taken up

by the expansion of the liner when heated by the internal combustion within the motor.

13. A composite cylinder for internal combustion motors comprising a main cylindrical wall, cooling means on the outer side of said wall, and a cylindrical liner secured concentrically within the said wall, the liner being made of metal having a higher coefficient of thermal expansion than

the metal of the said wall and having its external diameter less than the inner diameter of said cylinder wall to afford a clearance between the liner and wall adapted to be taken up by the expansion of the liner when heated by the internal combustion within the motor. 15

In testimony whereof I hereunto affix my signature.

ZAY JEFFRIES.
